UNITED STATES PATENT OFFICE

WILLIAM J. POPP, OF LOUDONVILLE, NEW YORK

DESIGN FOR A BOTTLE

Application filed April 10, 1933. Serial No. 47,743. Term of patent 14 years.

To all whom it may concern:

Be it known that I, WILLIAM J. POPP, a citizen of the United States, residing at Loudonville, county of Albany and State of New York, have invented a new, original, and ornamental Design for a Bottle, of which the following is a specification, reference being had to the accompanying drawing, forming part thereof in which

Fig. 1 is a side view of a bottle;

Fig. 2 is an edge view;

Fig. 3 is a plan view, and

Fig. 4 is a bottom plan view.

I claim:

The ornamental design for a bottle as shown.

WILLIAM J. POPP.
